[57] CLAIM

The ornamental design for a stadiometer, as shown and described.

DESCRIPTION

FIG. 1 is a perspective view of the stadiometer showing my new design;

FIG. 2 is a top plan view thereof, the bottom view being a mirror image thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is an enlarged portion of the scale, as indicated at 7 in FIG. 1; and,

FIG. 8 is an enlarged sectional view taken along the line 8—8 of FIG. 1.
